RAILWAY TRAFFIC CONTROLLING
APPARATUS

James J. Vanhorn, Swissvale, Pa., assignor to
The Union Switch & Signal Company, Swiss-
vale, Pa., a corporation of Pennsylvania

Application June 9, 1936, Serial No. 84,243

3 Claims. (Cl. 246—3)

My invention relates to railway traffic controlling apparatus, and more particularly to apparatus for indicating at a control point the position of a remotely located railway track switch.

I will describe one form of apparatus embodying my invention, and will then point out the novel features thereof in claims.

Referring to the accompanying drawing, the reference character T indicates the rails of a section of railway track including a power operated track switch W. As indicated diagrammatically on the drawing, switch W is actuated by a power switch machine SM controlled from a remote point by means of a manually operable switch lever L. Relay KR is the usual polarized indication relay for indicating the position and locked condition of the switch. When switch W is locked normal, as shown, a circuit is closed which may be traced from one terminal B of a suitable source of energy over contact 1 of an indication circuit controller controlled by the switch, the winding of relay KR, circuit controller contact 2 to the other terminal C of the same source, so that relay KR is energized to close its neutral contact 3 and to also close its polar contact 4 to the left as shown.

If the control lever L is moved from its left-hand position as shown to its right-hand position to reverse the switch, the switch will first become unlocked, opening contacts 1 and 2 to de-energize relay KR, and these contacts will close in the reverse position when the switch is fully reversed and locked, whereupon relay KR will be energized in the opposite direction so as to again close its neutral contact 3, but in this case the polar contact 4 will be closed to the right.

Relay KR is provided with repeating relays NKP and RKP, such as are customarily provided to control the circuits for signals governing traffic movements over the switch. Relay NKP is energized over a circuit from terminal B, through contact 3 and the left-hand polar contact 4 of relay KR, relay NKP to terminal C when relay KR is energized in the normal direction, and similarly relay RKP is energized over contact 3 and the right-hand polar contact 4 when relay KR is energized in the reverse direction, so that the condition of these relays reflects the position and locked condition of switch W. In some instances, the relay KR may be omitted, and the relays NKP and RKP may be controlled directly over the switch circuit controller contacts 1 and 2, or the circuits for relays NKP and RKP may also include contacts controlled by lever L arranged so that these relays when energized will

indicate correspondence between the switch and its control lever, but this is immaterial as far as my present invention is concerned.

For the guidance of the operator in controlling the switch, I provide at the point of control a track model or control panel having on its face a miniature representation of the track layout comprising a diagram t of the track section T and a miniature switch w at a location corresponding to that of the switch W. The miniature switch w is movable on the diagram to indicate the route to be taken by a train in passing over the switch W, and is connected mechanically to the armature of a control magnet or relay WK so that it occupies its normal position as shown in the drawing, when relay WK is energized. Relay WK is energized, when the switch is normal, over a circuit which may be traced from terminal B, through front contact 5 of relay NKP, and relay WK to terminal C. In this position the movable switch w covers a gap in the straight line portion of the diagram t so as to establish the continuity of that portion, and at the same time expose a similar gap shown just below the switch w which interrupts the continuity of the line representing the route from the siding to the main track of the diagram, to indicate that the track switch W occupies its normal position. When relay WK becomes deenergized, the miniature switch w is moved to its lower position to cover the last mentioned gap in the diagram and to expose the gap in the main line portion, to indicate that the track switch W is reversed.

One feature of my invention resides in the control of the miniature switch w by relay WK, in such a manner that this switch will remain in its last operated position while the track switch W is in transit from either one of its locked positions to the other. During this interval contact 3 is open so that relays NWP and RWP are both deenergized, but when the switch W is in transit from normal to reverse, the switch w will remain in the normal position because relay WK is held energized over a stick circuit which extends from terminal B, through back contact 6 of relay RKP, front contact 7 and winding of relay WK to terminal C. It will be apparent, therefore, that relay WK will not release to reverse the switch w until the switch W has been locked in its reverse position and contact 6 opens. When the switch W is in transit from reverse to normal the switch w will remain reversed, and will return to normal only when the track switch is locked normal and contact 5 closes to pick up relay WK.

Heretofore it has been customary to employ a

pair of magnets, one for each switch position, in order to cause a miniature switch to follow the movements of a track switch, but it will be readily apparent that the arrangement herein disclosed is to be preferred because of its simplicity, since it employs a simple neutral relay which is comparatively inexpensive and which occupies a minimum amount of the limited space that is available in track models of this character, particularly when complicated layouts are represented thereon.

Although I have herein shown and described only one form of apparatus embodying my invention, it is understood that various changes and modifications may be made therein within the scope of the appended claims without departing from the spirit and scope of my invention.

Having thus described my invention, what I claim is:

- 20 1. In combination with a stretch of railway track including a track switch, a control panel comprising a miniature representation of the stretch including a miniature movable switch operable to a normal or to a reverse position to indicate the position of the track switch, a relay for controlling said miniature switch, a pickup circuit for said relay closed when the track switch completes a movement from reverse to normal, and a stick circuit for said relay which opens when the track switch completes a movement from normal to reverse.
- 25 2. In combination with a railway track switch, a normal indication relay energized only when the switch is locked in its normal position, a reverse indication relay energized only when the switch is locked in its reverse position, a miniature switch operable to a normal or to a reverse position to indicate the position of the

track switch, a control relay, a pickup circuit for said control relay including a front contact of said normal indication relay, a stick circuit for said control relay including its own front contact and a back contact of said reverse indication relay, and means for operating said miniature switch to its normal position when said control relay is energized and to its reverse position when said control relay is deenergized.

3. In combination with a railway track switch, 10 an indication circuit controller controlled by the switch having normal contacts closed only when the switch is locked in its normal position and reverse contacts closed only when the switch is locked in its reverse position, a polarized indication relay, means for energizing said relay in a normal direction when said normal contacts are closed and in a reverse direction when said reverse contacts are closed, normal and reverse repeating relays, means for energizing the normal 20 repeating relay when the indication relay is energized in the normal direction and for energizing the reverse repeating relay when the indication relay is energized in the reverse direction, a control relay, a pickup circuit for said control 25 relay including a front contact of the normal repeating relay, a stick circuit for said control relay including its own front contact and a back contact of the reverse repeating relay, a miniature switch operable to a normal or to a reverse 30 position to indicate the position of the track switch, and means for operating said miniature switch to its normal position in response to the energization of said control relay and to its reverse position in response to the deenergization 35 of said control relay.

JAMES J. VANHORN.
